United States Patent Office

Des. 191,970
Patented Dec. 19, 1961

191,970

CHARCOAL GRILL OR SIMILAR ARTICLE

Charles W. Hecht, Fort Lauderdale, Fla.
(12 NW. 1st Ave., Dania, Fla.)

Filed Aug. 29, 1960, Ser. No. 61,936

Term of patent 14 years

(Cl. D81—10)

Fig. 1.

Fig. 2.

Fig. 3.

I claim:

The ornamental design for a charcoal grill or similar article, substantially as shown.
